CLAIM

The ornamental design for a wheel, as shown.

DESCRIPTION

FIG. 1 is a front elevational view of a wheel showing
my new design;

FIG. 2 is a rear elevational view thereof on a reduced
scale;

FIG. 3 is a side elevational view thereof on a reduced
scale; and

FIG. 4 is a sectional view thereof on a reduced scale
taken on the line 4—4 in FIG. 2 with the spokes broken
away in the middle for convenience of illustration.
